UNITED STATES PATENT OFFICE.

ANNA SPILMAN, OF NEW YORK, N. Y.

ABDOMINAL BAND.

Application filed July 7, 1922. Serial No. 573,814

To all whom it may concern:

Be it known that I, ANNA SPILMAN, a citizen of the United States, residing at New York, in the county of New York and State 5 of New York, have invented certain new and useful Improvements in Abdominal Bands, of which the following is a specification.

This invention relates to abdominal supports or bands and more particularly to a 10 novel and improved design of wearing apparel to take the place of the common type of corset having stiffening members therein such as corset steels, etc., and one which 15 can be comfortably worn without bodily injury and without sacrificing personal appearance.

It is well known that physical weakness due to abdominal operations is aggravated 20 and continued over a long duration of time by reason of improper wear of certain apparel, particularly corsets, and many people inclined to be stout, become permanently injured by reason of tight lacing 25 which has the tendency to force the abdominal organs downward instead of upward. The abdominal muscles become cramped causing pain and the internal organs are consequently affected preventing 30 their proper functioning by reason of the unnatural strain imposed as well as the retardation of the proper blood circulation incident to incorrect wearing apparel.

The primary object of my invention therefore 35 is to provide an abdominal band or support which takes the place of a corset and at the same time assists in proper supporting the lower walls of the abdomen in the natural manner without injuring the internal organs and at the same time affording 40 comfort without sacrificing appearance.

Another and equally important object of my invention is the provision of an abdominal support or band of the character above 45 set forth which is practical, highly efficient, neat in appearance and design, comfortable when worn and otherwise capable of being manufactured at a comparatively low cost whereby its commercial possibilities are 50 greatly enhanced.

I attain the above objects and others by the preferred form of the invention exemplified in the accompanying drawing, wherein:

55 Fig. 1 is a rear view of the band.
Fig. 2 is a front view thereof.

Fig. 3 is a plan partly in section.

Referring now to the drawings wherein like reference characters designate corresponding parts on the drawing, 5 designates 60 the short side and 6 the longer overlapping side of the band which is of substantial width, the short side having a row of buttons 7 sewed to the outer edge and the longer side 6 having a buttonhole strip 8 whereby the band may be secured as is well understood.

The inner, free ends of the short and longer side of the band are sewed or fastened in any well known manner to a vertical strip 70 or insert 9 extending from the top 10 to the bottom 11 to allow for sufficient adjustment, the said strip or insert being disposed on the inner side of the band as shown by Fig. 1 of the drawing. A row of eyelets 12 and lacing 13 passing therethrough is provided which permits the band to be properly adjusted to the size and comfort of the individual.

In order to give sufficient stiffness to the 80 back of the band and on the opposite side of the strip or insert, I have provided pockets on each side of the row of eyelets to permit of the insertion of a pair of flexible stays whereby the same may be removed 85 when it is desired to launder the device.

Reference being had to Figures 1 and 3 of the drawing, it will be seen that I have provided an inner abdominal supporting belt 14, the ends of which are preferably 90 sewed or stitched along the seems joining the insert 9 with the parts 5 and 6, said belt of course being of substantial width and intermediate the top and bottom edges 10, 11 and in addition being provided with eyelets 95 and buttons 15. It will thus be seen that when the belt is properly fastened that it will have the tendency to draw up and support the lower abdominal muscles and with perfect comfort to the individual since the 100 proper adjustment can be made by drawing in the laces and the insert or letting the same out to suit the person.

The bottom edge 11 of the support or band is also cut away to provide tabs 15, 16, 17 and 18 each of which have a buttonhole to receive the removable garter 20 for attachment to the stockings as is well understood. In order to properly position the supporting belt 14, I have also provided a pair of garters 14^a, attached adjacent the bottom thereof and in proximity to the front, free ends 110

which are fastened, so that when the garters are secured to the stocking, they will counteract the tendency of the band to move upwardly. The garters may be of course be removed when it is desired to wash the garment and subsequently be replaced. A pocket 22 formed with a flap 23 is attached in any well known manner to the longer side 6 and constitutes a secret, valuable receiving 10 depository instead of carrying articles of value such as jewelry, in the stocking.

While I have illustrated and described my invention with some degree of particularity, I realize that in practice various alterations therein may be made. I therefore reserve the right and privilege of changing the form of the details of construction or otherwise altering the arrangement of the correlated parts without departing from the 20 spirit of the invention or the scope of the subject matter being claimed.

Having shown and described my invention

what I now claim as new and desire to secure by Letters Patent of the United States is:

An abdominal support comprising two substantially wide sections of unequal length having fastening means at their free ends for connecting the same to one side of the medial line of the support, a strip extending 30 from the top and bottom connecting said sections at their inner ends, lacing for adjusting said strip and the sections, stiffening members within the ends of the sections and outside of the strip, and a substantially 35 wide body band of a length less than the connected sections, said band being attachable to the inner side of the connected ends of the sections and intermediate the top and bottom thereof, said band being adjustable 40 with the strip when the lacing is drawn taut or loosened.

In testimony whereof I affix my signature.

ANNA SPILMAN. [L. s.]
